UNITED STATES PATENT OFFICE.

GEORGE WILLIAM KORPER, OF BROOKLYN, NEW YORK.

DESIGN FOR A PRECIOUS OR IMITATION STONE.

56,977.

Specification for Design.

Patented Jan. 25, 1921.

Application filed August 10, 1920. Serial No. 402,702. Term of patent 3½ years.

To all whom it may concern:

Be it known that I, GEORGE WILLIAM KORPER, a citizen of the United States, residing in the borough of Brooklyn, county of Kings, city and State of New York, whose post-office address is No. 639 East 18th street, Brooklyn, New York, have invented a new, original, and ornamental Design for Precious and Imitation Stones, of which the following is a specification, reference being had to the accompanying drawing, forming a part thereof.

Referring to the drawing:

Figure 1 is a top-view of a stone showing my new design.

Fig. 2 is a side view of a stone showing my new design.

I claim:

The original and ornamental design for a precious or imitation stone, as shown.

GEORGE WILLIAM KORPER.
